UNITED STATES PATENT OFFICE

CHARLES N. ARNOLD, OF CHAUMONT, NEW YORK

SNOWPLOW

Application filed February 10, 1932. Serial No. 592,102.

This invention relates to a snowplow.

It is primarily aimed to provide a novel construction which is adapted to be pushed by a truck or the like and which will not require special fastening in order to couple or arrange the same in operative relation with respect to the truck.

Another object is to provide a novel construction in which the discharge member is positively operated and in front of which colter or dividing means for plowed snow is provided.

Still further an object is to provide a novel observation means not likely to become blurred or affected by agitation of the snow.

The more specific objects and advantages will become apparent from a consideration of the description following taken in connection with accompanying drawing illustrating an operative embodiment.

In said drawing:

Figure 1 is a plan view showing the plow in connection with a truck,

Figure 2 is a side elevation of the parts of Figure 1,

Figure 3 is a longitudinal sectional view taken on the line 3—3 of Figure 1,

Figure 4 is a front elevation of the plow, and

Figure 5 is a cross sectional view taken on the line 5—5 of Figure 2.

Referring specifically to the drawing, the plow comprises a metallic or other body 10 of suitable size constituting a plow and adapted to be pushed into snow, the forward end of the body being arranged diagonally at 11. Such body adjacent the rear has a closed wall 12, side walls 13 and 14, a top wall 15, and a bottom wall 16. Said bottom wall 16 inclines upwardly and rearwardly and delivers snow into which the plow 10 is pushed, to a discharging fan at 17, the top wall 15 having an enlargement 18 to accommodate operation of such fan and a discharge opening 19 being provided in the walls 13 opposite the fan, a flange 20 being provided in the face of the discharge opening 19. Said fan has a shaft 21 suitably journaled in bearings 22 and 23 provided on the plow and

from which shaft arms 24 radiate, having blades 25 fastened thereto.

The shaft 21 is driven in any suitable manner as by means of a motor 26 located in a suitable housing 27 extending from the wall 12. Motor 26 may be of any desired type, for instance, an internal combustion engine, and may have a transmission mechanism between the same and shaft 21 to drive the latter at different speeds according to the speed of advance of the plow.

A longitudinally disposed observation tube is provided at 28 and connected by brackets 29 to the plow 10. The tube 28 is preferably closed at the front by a transparent glass 30. It will be noted that the tube extends to the front of the device forwardly of the zone of plowing of the snow so that there will be little likelihood of the glass becoming clogged or vision through the tube obscured.

It will also be noted that a plurality of vanes or colters 31 depend from the wall 15 and are arranged in the path of the snow through the plow. Such colters or vanes serve to separate the snow to facilitate its discharge by the fan 21.

It will also be noted that wings 32 extend rearwardly beyond the wall 12 and that a truck 33 or other propelling body, is adapted to drive between the wings 32 and abut the wall 12, thereby forming a sufficient connection and as the truck is driven, to drive or push the plow forwardly. It will also be realized that the inner end of the observation tube 28 will be located adjacent the driver's position of the truck.

Various changes may be resorted to provided they fall within the spirit and scope of the invention.

What is claimed is:

1. A plow of the class described having a hollow body adapted to be pushed into the snow, said body having a discharge opening, a fan arranged to be engaged by the snow and to discharge the same through the opening, wings extending rearwardly from the body to define a zone for engagement by a propelling vehicle, said body having a wall at an angle to the wings adapted for abutment by the said vehicle.

2. A plow of the class described having a hollow body adapted to be pushed into the snow, said body having a discharge opening, a fan arranged to be engaged by the snow and to discharge the same through the opening, wings extending rearwardly from the body to define a zone for engagement by a propelling vehicle, said body having a wall at an angle to the wings adapted for abutment by the said vehicle, a motor to drive said fan, and a casing for said motor connected to the last mentioned wall and to one of said wings.
3. A plow of the class described having a hollow body adapted to be pushed into the snow, said body having a discharge opening, a fan arranged to be engaged by the snow and to discharge the same through the opening, wings extending rearwardly from the body to define a zone for engagement by a propelling vehicle, said body having a wall at an angle to the wings adapted for abutment by the said vehicle, and an observation tube supported on the body and extending forwardly of the zone of fanning.
4. A plow of the class described having a hollow body adapted to be pushed into the snow, said body having a discharge opening, a fan arranged to be engaged by the snow and to discharge the same through the opening, wings extending rearwardly from the body to define a zone for engagement by a propelling vehicle, said body having a wall at an angle to the wings adapted for abutment by the said vehicle, and colter means on the plow body in the path of the snow to the fan.
5. A plow of the class described having a hollow body adapted to be pushed into the snow, said body having a discharge opening, a fan arranged to be engaged by the snow and to discharge the same through the opening, wings extending rearwardly from the body to define a zone for engagement by a propelling vehicle, said body having a wall at an angle to the wings adapted for abutment by the said vehicle, an observation tube supported on the body and extending forwardly of the zone of fanning, and an inclined bottom for said body extending upwardly and rearwardly.

In testimony whereof I affix my signature.
CHARLES N. ARNOLD.
